UNITED STATES PATENT OFFICE.

LORENZ C. ACCOLA, OF BRUSH, COLORADO.

SHOULDER-BRACE.

No. 918,940.

Specification of Letters Patent.

Patented April 20, 1909.

Application filed May 2, 1908. Serial No. 430,474.

To all whom it may concern:

Be it known that I, LORENZ C. ACCOLA, a citizen of the United States, and a resident of Brush, in the county of Morgan and State of Colorado, have invented a new and Improved Shoulder-Brace, of which the following is a full, clear, and exact description.

My invention relates to shoulder braces, and has for its object to provide a shoulder brace with few parts, which can be adjusted readily and which will not cause the wearer any inconvenience.

Curved metal springs are provided, which are adapted to hold the shoulders back in place without confining or restricting the movements of the body as is done with the ordinary shoulder braces which are in the nature of bandages.

The invention is simple in construction and can be manufactured at little cost.

Another object of the invention is to so adjust the members of the device that they are adapted to lift the shoulders as well as to hold them back.

Still another object is to provide means which may be fastened to an ordinary waistband and which may be adjusted to hold the shoulders back under varying tension.

Other objects of the invention will appear in the following more complete description.

In this specification I will describe my preferred form of the invention, but I do not limit myself thereto as I consider myself entitled to all forms and embodiments of the invention which may be held to fall within the scope of the appended claims.

Reference is to be had to the accompanying drawings, forming a part of this specification, in which similar characters of reference indicate corresponding parts in all the figures, in which—

Figure 1 is a rear elevation of the invention; Fig. 2 is a side elevation of the same; and Fig. 3 is a sectional view on line 3—3 of Fig. 1.

By referring to the drawings, it will be seen that I use a metallic spring 1, which spring is U-shaped at its middle portion, which is adapted to be disposed on the back of the wearer, this middle U-shaped portion 2 being secured to a cross member 3 and a plate 4, the plate 4 being secured to the sides of the metal U-shaped portion 2 of the spring 1, but leaving an opening at the

bottom between the said U-shaped portion 2 and the said plate 4.

A slide 5 is pivoted to the cross member 3, this slide 5 extending into the opening between the plate 4 and the bottom of the U-shaped portion 2 of the spring 1. In this slide 5 is introduced a leaf spring 6, which is so constructed that it will have a curve as shown in Fig. 2, when it is at rest.

The two elastic members 7 are secured to the cross member 3, one at either side of the slide 5, and these elastic members, which may be covered with silk, cotton or other material, extend down through the opening between the plate 4 and the bottom of the U-shaped portion 2 of the spring 1, until they reach the lower terminal of the leaf spring 6, where they are passed through orifices in the said leaf spring 6 and are knotted as shown in Fig. 2. The leaf spring 6 is adapted to be secured to a waistband 8 as shown in the drawings. Each side of the spring 1, above the cross member 3, is curved forwardly, outwardly, downwardly and then backwardly, in order to make the spring 1 fit the curvatures of the shoulders and arms, there being a pad 9, secured to each side of the spring 1, these pads being so disposed that they will act on the body and prevent chafing.

In using my invention, the free portions of the spring 1 are adjusted over the shoulders and under the arms of the wearer, and the leaf spring 6 is then secured to the waistband 8, which may, however, be secured to the leaf spring 6, in which case the waistband 8 is then strapped around the body of the wearer. After the shoulder brace has been put on the body of the wearer, it is adjusted by means of the elastic members 7, which are drawn through the orifices in the leaf spring 6, until the proper tension is obtained, and the terminals of the elastic members 7 are knotted to hold them in place relatively to the leaf spring 6. By drawing the elastic members through the orifices in the leaf spring 6, the leaf spring 6 is curved, and by means of the said elastic members and the said leaf spring, a varying backward pressure on the spring 1 is obtained, which accomplishes the desired result in holding the shoulders of the wearer back in position. Inasmuch as when the spring 1 is drawn back by means of the

leaf spring 6 and the elastic members 7, the terminals of the spring 1, which are under the arms of the wearer, are lifted, as the principal portions of the spring 1 are drawn 5 rearwardly.

My brace is adapted to raise the shoulders, as well as draw them back in position and prevent the shoulders from becoming rounded.

Having thus described my invention, I 10 claim as new and desire to secure by Letters Patent:

1. A shoulder brace with a metal spring, the middle portion of which is U-shaped, the arms being curved forwardly, outwardly, downwardly and rearwardly, to 15 suitably engage the body, a slide secured to the said metallic spring, and a leaf spring which is adapted to engage the slide, the leaf spring being adapted to be secured to a 20 waistband.

2. A shoulder brace with a metal spring which has its central portion secured to a cross member and which has its arms curved forwardly, outwardly and downwardly, a 25 slide pivoted to the said cross member, a leaf spring adapted to engage the slide, the leaf spring being adapted to engage the waistband, and means by which the leaf spring may be curved.

3. In a shoulder brace, a member which is 30 adapted to press rearwardly and upwardly,

a body member, the said first named member being secured to the body member, the body member being adapted to be held back under varying degrees of pressure, and means to so 35 hold the body member.

4. In a shoulder brace, a member which is adapted to press rearwardly and upwardly, a body member, the said first named member being secured to the body member, a spring 40 which has a sliding engagement with the body member, and springs to hold the spring in varying positions relatively to the body member.

5. A shoulder brace with a metal spring, 45 a slide secured to the said metal spring and a leaf spring which is adapted to engage the slide, the leaf spring being adapted to be secured to a waistband.

6. A shoulder brace with a metal spring, 50 a slide, the metal spring being secured to the slide, a leaf spring which is adapted to engage the slide, the leaf spring being also adapted to engage the waistband, and means by which the leaf spring may be curved. 55

In testimony whereof I have signed my name to this specification in the presence of two subscribing witnesses.

LORENZ C. ACCOLA.
